Primary Examiner—M. H. Tung**Attorney, Agent, or Firm**—Banner & Witcoff, Ltd.**[57] CLAIM**

The ornamental design for an outer surface portion of an electronic enclosure, as shown and described.

DESCRIPTION

FIG. 1 is a perspective view of an outer surface portion of an electronic enclosure showing my new design;
 FIG. 2 is a front elevational view thereof;
 FIG. 3 is a top plan view thereof;
 FIG. 4 is a left side elevational view thereof; and,
 FIG. 5 is a right side elevational view thereof.
 The broken line drawing of a portion of an electronic enclosure in all figure views is for illustrative purposes only and forms no part of the claimed design.
